UNITED STATES PATENT OFFICE.

JOHN F. H. KING, OF PORT RICHMOND, NEW YORK.

FIRE-ESCAPE LADDER.

SPECIFICATION forming part of Letters Patent No. 228,647, dated June 8, 1880.

Application filed March 2, 1880. (Model.)

To all whom it may concern:

Be it known that I, JOHN F. H. KING, of Port Richmond, in the county of Richmond and State of New York, have invented a new and Improved Fire-Escape, of which the following is a specification.

My invention relates to the class of portable fire-escapes which are moved from place to place upon a truck and elevated at the place of use.

The invention consists in a mast mounted upon a truck, so as to be raised and supported in a vertical position for sustaining a swinging ladder when the escape is in use, and to be lowered with the ladder into a horizontal position on the truck for transportation.

The details of construction are more fully set forth hereinafter.

In the accompanying drawings, Figure 1, Sheet 1, is a sectional elevation of my fire-escape in position for use. Fig. 2 is a section transversely of the truck, showing the connection of the mast-slide to the truck and the truck-braces. Fig. 3 is a view showing the connection of the ladder to the mast. Fig. 4, Sheet 2, is an elevation, showing the fire-escape in position for transportation.

Similar letters of reference indicate corresponding parts.

The supporting-truck *a* is mounted on wheels and carries a sliding block, *b*, fitted to move in grooves *c* in the sides of truck *a*, to which block *b* is connected one half of the platform *d*. The other half of *d* is fixed to the truck *a*, and when in position, as shown in Fig. 1, the mast *e* passes through the center of platform *d*, through block *b* and truck *a*, to the ground, where its end rests in a step, *f*.

g g, Fig. 2, are braces hinged to *d*, and extending to the ground at each side of the truck to steady it. *h h* are ropes or chains from braces *g* to step *f*, for retaining the braces in position. *i* is a ladder fixed to mast *e*, extending from platform *d* to the cross-tree *k* of the mast, and having fitted to its lower end the shafts of barrels *l m*, that are used for elevating the ladder and raising and lowering the basket, *a*, hereinafter described. *n* is the main ladder, hung by trunnions *o* on cross-tree *k*, so that about two-thirds of its length will be

above the mast when elevated. It is raised into the position shown in Fig. 1 by ropes *p*, which are connected to the mast *e* by a link at *q*, pass through links at the lower end of ladder *n*, and from thence around barrel *l*, so that by winding ropes *p* on the barrel *l* the ladder *n* will swing on its trunnions to a more or less elevated position.

At the lower end of ladder *n* is a ladder, *q*, hung upon a bar, *r*, that is fitted to slide in grooves in the sides of ladder *n*, so as to be drawn down to rest on the ground when the escape is elevated. At the upper end of ladder *n* is a sheave, *s*, through which passes a rope, *t*, from barrel *m*, and *u* is a basket hung on rope *t*, which can be used to lower persons from windows.

The ladder *n* is braced by guy-ropes attached at its ends and passing through stretchers *v*, that extend from the trunnions *o*, which stretchers may be turned down by hand parallel with ladder *n* when it rests on the truck. When the mast is raised clear of the truck-floor the hoisting-rope is slackened and the foot of the mast started in the right direction by suitable mechanism.

To lower the mast *e* and ladder *n*, I make use of a windlass, *w*, journaled on truck *a* and carrying a rope, *w'*, that passes down through block *b* and mast *e*, and is connected to the fixed portion of platform *d* above block *b*. By winding rope *w'* the mast and ladder are raised until the end of the mast is above the lower side block, *b*, when rope *w'* is slackened to permit the block *b* and one half of platform *d* to slide upon the truck, the foot of the mast moving with them, and its other portion lying upon the fixed part of platform *d*. At the same time the windlass *l* is turned to slack ropes *p* until the mast and ladder lie upon the truck in the position shown by Fig. 4. The braces *g g* are then to be raised upon the truck-platform, pushed inward, and the apparatus is ready for transportation, and can be elevated by a reversal of the operation.

I am aware that the swinging stretchers for guy-ropes and the windlass-rope and basket are not new in fire-escapes; but

What I claim as new and of my invention is—

1. The combination, with mast *e*, of the ladder *n*, trunnion at top of said mast, and the ladder *g*, sliding in said ladder *n*, as and for the purpose specified.
- 5 2. In a fire-escape, the combination, with a truck, *a*, of a mast, *e*, swinging ladder *n*, windlass *l*, and rope *p*, arranged for operation substantially as described.
- 10 3. The combination, with the mast *e*, ladder *n*, and truck *a*, of the sliding block *b*, platform *d*, windlass *w*, and rope *w'*, substantially as and for the purposes set forth.
- 15 4. The braces *g*, step *f*, and ropes or chains *h*, in combination with the truck *a* and mast *e*, substantially as and for the purposes described.
- 20 5. The combination of the mast *e* and fixed ladder *i*, having windlass *w*, with the ladder *n*, having top pulley, *s*, a rope being made to pass from windlass and over said pulley, as and for the purpose specified.

JOHN F. H. KING.
